MECHANICAL STOKER

Lorn Campbell, Jr. and Anthony von Haase, Lakewood, Ohio, assignors, by mesne assignments, to said Campbell, Jr.

Application December 1, 1937, Serial No. 177,641

10 Claims. (CL. 110—115)

This invention relates to stokers and has for its objects to provide a portable device of this kind which is capable of being used in connection with existing furnaces, which is of a construction to prevent ignition of fuel in the stoker itself, which will not grind or break the fuel in the feeding process and which need not contain or be associated with any forced draft mechanism.

More limited objects are to provide a simple, practical and smoothly operating stoker of the overfeed type wherein the coal or similar fuel is catapulted from the stoker into the furnace, to provide for adjustment of the catapulting mechanism so as to vary the catapulting force and the angular position of the fuel holding element at which the fuel is projected therefrom whereby to vary the trajectory of the fuel to accommodate the device to existing furnaces of differing construction such as different sizes of furnace feed doors and different lengths of feed extensions between the firepot and the furnace door as well as for directing the fuel to a selected desirable point in firepots of different sizes, and to provide for sudden arrest of the fuel holding element from a high velocity whereby to discharge the fuel cleanly in a compact mass and avoid excessive scattering.

A further object is to provide an auxiliary feeding element preferably operated in timed relation with the catapulting device and adapted to feed fuel from the storage hopper and assist in loading the catapulting device, such auxiliary feed means preferably being adjustable as to length of stroke.

A further and very important object of the invention is to provide for actual or substantial contact of a fuel receiving element of the catapulting device with the fuel supporting surface from a point in advance of its engagement with the fuel mass whereby to prevent breaking or grinding of fuel particles or wedging thereof between the fuel receiving element and the fuel supporting surface.

A still further object is to provide a novel and superior drive for the catapulting device, the same being of such construction as to move the fuel receiving part of such catapulting device by a yielding drive at a low rate of speed while it is being loaded and elevated to throwing position whereby to avoid excessive motor load due to lumps while the fuel receiving device is leaving the fuel heap after being loaded, and to cause it to be suddenly and greatly accelerated through a portion of its revolution and then suddenly arrested whereby to project the fuel into the fire-

box of the furnace and thereafter to move slowly until the catapulting portion of the next revolution is again reached.

An important feature of the device disclosed is its light weight construction combined with portability whereby it readily can be wheeled into position at the furnace or removed therefrom and wheeled to the coal bin for filling. Also, it can be easily pulled away for access to the furnace for starting a fire or for removal of ashes.

Other and more limited objects will be in part apparent and in part pointed out hereinafter in connection with the accompanying drawings wherein Fig. 1 is a diagrammatic transverse section through a furnace of usual construction and showing our improved stoker in operative relation thereto; Fig. 2 is a section on the line 2—2 of Fig. 1, showing the full receiving element or shovel in its fuel-distributing position; Fig. 3 is an enlarged fragmentary section taken on the same plane as Fig. 2; Fig. 4 is an enlarged section on the line 4—4 of Fig. 3; Fig. 5 is a section on the line 5—5 of Fig. 3; Fig. 6 is an enlarged section on the line 6—6 of Fig. 1; Fig. 7 is a detail perspective of one end of a sleeve carrying the fuel holding element of the catapulting device; Fig. 8 is a perspective of a trigger element cooperating with said sleeve and a cam on the power shaft; and Fig. 9 a detail in section showing a modification of the shovel.

General construction and operation

In the drawings, the numeral 10 indicates generally a furnace of usual construction having a firepot 11 opening through a projection or feeding neck 12 to the exterior. The door normally closing the outer end of the feeding neck 12 is shown as having been opened and our improved stoker is shown as it would appear after having been pushed into position to close the door opening. The stoker comprises a supporting base 13 housing the driving motor (which may be electric, hydraulic, or the like) and which is mounted on vertically adjustable legs 14 resting on casters 14a, a hopper portion 15 adapted to contain a charge of fuel, a feed chamber 16 separated from the hopper 15 by a heat insulating baffle 17, a connecting neck 18 adapted to connect the feed chamber 16 in communication with the fuel neck 12 of the furnace, and feed means comprising a catapulting device indicated generally by the numeral 19 and an auxiliary feeding device 20.

In operation, the hopper 15 is supplied with coal, or similar lump or granular fuel, the largest particles of which are of a size readily to pass

between the lower end of the baffle 17, comprising spaced plates to provide heat insulation and cooling and thereby prevent fuel in the hopper from sticking, and the auxiliary feed slide 20, and the driving motor for the catapulting device 19 is started. The device 19 includes a rotating fuel receiving or shovel element indicated generally by the numeral 21 which rotates in a counter-clockwise direction, as seen in Fig. 1. Responsive to operation of the motor, the shovel 21 rotates, coming into contact or substantial contact with the bottom wall 22 of the feed chamber 16 at approximately the level of its axis of rotation and moving in contact or substantial contact therewith, much in the manner of a shovel being moved along a floor, until it has received a load of fuel. The slide 20 preferably is so timed as to move toward the left to its extreme position in that direction approximately at the time the shovel element 21 is in position to be fully loaded. The slide 20 then begins to recede while the shovel continues to move in a counter-clockwise direction until it reaches approximately the point which it occupies in Fig. 1 whereupon it stops while the projecting means is being conditioned to impart a sudden acceleration which projects the fuel into the firepot.

Catapulting device

Supported by journals 23^a and 23^b carried by the side walls of the feed chamber 16 is a power shaft 24 which is driven by an electric motor 25 supported on a plate 25^a through the medium of a gear reduction means comprising reducing gear mechanisms at 26 and 26^a connected by a shaft 26^b and protected by a cover 26^c. Keyed on the shaft 24 is a drum 27 on the outside of which is received a helical spring 28 one end of which is connected to said drum 27 as by having one end 29 received in an opening of the head 30 in such drum. Rotatable on the shaft 24 is a sleeve 31 which carries the shovel element 21 through the medium of an arm 32 received in a suitable transverse bore in an enlarged portion 33 thereof. The other end 34 of the spring 28 is received in a suitable opening in the enlarged portion 33 of the sleeve 31. The spring 28 is protected by a cover sleeve 28^a mounted as shown. The sleeve 31 extends to the outside of the feed chamber 16 and terminates in an enlarged portion 35 secured thereto and provided with a notch 36. Secured to the shaft 24 adjacent the portion 35 is a cam 37. The element 23 which carries the journal 23^b is rotatably and adjustably mounted on the wall 16^a of the feed chamber 16, being held in any adjusted position by bolts 37^a received in slots 37^b and suitable openings in the wall 16^a. Pivoted to the element 23 is a detent 38 movable through an opening 23^c in the element 23 and urged by a spring 39 toward the elements 35 and 37. A portion 40 of the detent 38 rides on the element 35 and drops into the notch 36 as the sleeve 31 rotates.

The engagement of the element 40 in the notch 35 arrests the rotation of the sleeve 31 and consequently of the shovel 21 and holds it while the shaft 24 continues to rotate, consequently energizing the spring 28. The spring 28 is energized by being unwound whereby, when it is released, it will wind up on the drum 27 and bring the shovel 21 to a sudden stop whereby to cleanly and completely discharge its load into the furnace. If the shovel were free to swing past the discharge point, the load would tend to great scattering and excessive piling up of fuel in the

feed neck of the furnace. Since the shaft 24 continues to rotate, the cam 37 will, after a predetermined interval, acting through the medium of the adjustable set screw 41, lift the portion 40 out of the notch 36 thereby releasing the sleeve 31. The spring 28 having been energized by unwinding will, upon the release of the element 40 from the notch 36, suddenly accelerate the rotation of the sleeve 31 and consequently the shovel 21 (the same being suddenly stopped by the re-winding of the spring) and project the fuel into the furnace. The spring being again restored to normal, the cycle just described is repeated. The adjustment of the element 23 and the adjustability of the set-screw 41 which passes through the opening 41^a in the trigger 38 make possible adjustment of the amount of unwinding of the spring 28 before the shovel is released and the point of release as well as the point at which the motion of the shovel is arrested by the winding up of the spring 28 on the drum 27. The sleeve 28^a assures even flexing of the spring 28 along its whole extent and protects the moving parts which it encloses from ingress of fuel particles or dust.

Auxiliary feed

Pivoted on the wall of the feed chamber 16 as indicated at 42 is a lever 43 comprising a flat plate with a bifurcated upper end terminating in ears 44 constituting cam followers and cooperating with a cam 45 on the shaft 24. Upon rotation of the shaft 24 the lever 43 is oscillated thereby imparting an oscillatory motion to the lever 46 pivoted below the floor 22 of the feed chamber 16, as indicated at 47 and extending into an opening 48 in the lever 43. The lever 46 is provided with a slot 49 which receives a pin 50 carried by a link 51 which is in turn pivotally connected to the slide 20, as indicated at 52, by a pin extending through a slot 52^a in the bottom wall 22.

It will be obvious that by adjusting the position of the cam 45 with respect to the shaft 24, the slide 20 can be caused to occupy any desired relation to the shovel 21 at the time of loading the latter. As previously stated, it is desirable that the slide 20 should advance to its extreme left position as seen in Fig. 1 just as the shovel 21 is loaded. This, however, is not absolutely necessary and variations from this timing are within the scope of the invention. It will be obvious that such resistance as the loading of the coal offers to the motion of the shovel will tend to flex the spring 28 and that any unevenness of resistance to the motion of the shovel will tend to be "smoothed out", thereby reducing the maximum power requirement and consequently the capacity requirements for the driving motor.

The stroke of the slide obviously can be varied by varying the position of the pin 50 in the slot 49. This is accomplished through the medium of a bell crank lever 53 terminating at one end in an adjusting handle 54 adapted to be engaged with any one of a plurality of teeth (not shown) and connected at its inner end by a link 56 to the power transmitting link 51.

We prefer to make the shovel element of the catapulting device narrower than the feed chamber 16 and at the same time to have it operate against a fuel heap not substantially wider than itself. Accordingly, we provide plates 57 welded or otherwise secured to the bottom and side walls of the fuel chamber and effectively narrowing the

work space at the bottom to approximately the width of the shovel. One of the plates 57 has an opening 57^a within which the lever 43 works. In the event a hot cinder should fall into the 5 stoker, it would, thus, be promptly returned to the furnace.

As above stated, it is an important feature of the invention to cause the forward edge of the shovel 21 to be in actual or substantial contact 10 with the bottom wall of the feed chamber through the first part of the loading operation. The present preferred manner of accomplishing this result is to provide the shovel 21 with a resilient forward edge 58 which will be flexed by contact 15 with the wall 22 and will resume its free position only at or after the loading of the shovel has been completed. We have found that this construction results in proper loading of the shovel and prevents breaking, grinding or wedging of 20 fuel particles between the shovel and the floor of the feed chamber. Good results can be had by making the edge of the shovel non-resilient but locating it substantially exactly far enough from the power shaft 24 to contact the curved 25 wall 22, as shown in Fig. 9.

The control for our improved stoker may be manual, semi-automatic or fully automatic and, per se, forms no part of the present invention.

From the foregoing it will be clear that we 30 have provided a stoker well adapted for its intended purpose and while we have shown and described the present preferred embodiment we wish it understood that we are not limited to the details of the disclosure but only in accordance 35 with the appended claims.

Having thus described our invention, what we claim is:

1. In a mechanical stoker, in combination, a fuel chamber, a power shaft rotatable therein, a 40 rotatable sleeve on said shaft, a yieldable connection between said shaft and said sleeve, a shovel carried by said sleeve, means for arresting the motion of said sleeve at a predetermined point in its revolution and means for releasing 45 said sleeve arresting means at a predetermined point in the revolution of said power shaft.

2. In a mechanical stoker, the combination with a fuel chamber, a shovel therein and means for rotating the same to cause it to be loaded with 50 fuel once each revolution, said last means comprising a power shaft, means for rotating said power shaft at a low velocity, and means associated with said power shaft and operated thereby for rapidly accelerating and suddenly arresting 55 the motion of the shovel within a limited portion of each revolution subsequent to loading thereof whereby to discharge fuel therefrom.

3. In the combination recited in claim 2, said fuel chamber being generally wider than said shovel but tapering to a width not greatly exceeding that of said shovel at the bottom in the region where loading of the shovel is effected. 60

4. In the combination recited in claim 2, a hopper connected at the bottom with the fuel

chamber, an auxiliary feeding device comprising a slide reciprocable along the bottom of said hopper and said fuel chamber and means for operating said slide in timed relation to said shovel and in such phase relation thereto as to 5 be at its innermost position with respect to the fuel chamber at approximately the time when the shovel is completely loaded.

5. In the combination recited in claim 2, said shovel being provided with a resilient lip at its 10 forward edge adapted to be flexed by contact with the bottom of the fuel chamber during the loading operation.

6. In the combination recited in claim 2, said fuel chamber having a substantially horizontal 15 bottom portion and an upstanding wall merging with said horizontal portion by a curved portion substantially concentric with said power shaft, said shovel being mounted at such a distance from said power shaft that its forward edge 20 moves over said curved wall portion in substantial contact therewith.

7. In a mechanical stoker, in combination, a fuel chamber, a power shaft rotatable therein, a rotatable sleeve on said shaft, a yieldable connection between said shaft and said sleeve, a shovel carried by said sleeve, adjustable means for arresting motion of said sleeve at a predetermined point in its revolution and adjustable means for releasing said sleeve arresting means 30 at a predetermined point in the revolution of said power shaft.

8. In the combination recited in claim 2, an auxiliary feeding device for pushing fuel toward said shovel and means operated by said power 35 shaft for operating said auxiliary feeding device in such timed relation to said shovel as to push fuel toward the shovel as the shovel is being loaded.

9. In a mechanical stoker, in combination, a fuel chamber, a power shaft rotatable therein, a rotatable sleeve on said power shaft, a yieldable connection between said shaft and said sleeve, stop means carried by said sleeve, a trigger carried by said fuel chamber having a portion 40 adapted to engage said stop means to arrest rotation of said sleeve, a cam on said power shaft, and means carried by said trigger adapted to be engaged by said cam for disengaging said trigger 45 from said stop means.

10. In a mechanical stoker, in combination, a fuel chamber, a power shaft rotatable therein, a rotatable sleeve on said power shaft, a yieldable connection between said shaft and said sleeve, stop means carried by said sleeve, a trigger 55 adjustably carried by said fuel chamber having a portion adapted to engage said stop means to arrest rotation of said sleeve, a cam on said power shaft, and adjustable means carried by said trigger adapted to be engaged by said cam for disengaging said trigger from said stop means. 60
